BOWLING GAME TABLE

Ernest A. Lakamp, Forest Lake, Minn.

Filed Oct. 2, 1962, Ser. No. 71,959

Term of patent 14 years

(CL. D34—5)

FIGURE 1 is a perspective view of a bowling game table embodying my design;

FIG. 2 is a plan view of the same;

FIG. 3 is a side elevational view of the same;

FIG. 4 is an end elevational view of the table as seen from the left of FIG. 2;

FIG. 5 is an end elevational view of the table as seen from the right of FIG. 2, and

FIGS. 6 and 7 are fragmentary sectional views taken respectively on the lines 6—6 and 7—7 of FIG. 2.

The dominant features of my design reside in the portions shown in full lines.

I claim:

The ornamental design for a bowling game table, as shown and described.
